UNITED STATES PATENT OFFICE.

ALEXANDER T. GIBSON, OF OAKLAND, CALIFORNIA.

WINDOW LATCH.

Application filed September 8, 1925. Serial No. 55,138.

The present invention relates to improvements in window latches of the type adapted for locking either or both of the upper and lower sashes of a window in various positions of adjustment.

The object of the invention is to provide for latching the upper sash to the lower sash and to cause the sash members when so latched to bind on the walls of their guides and thus be rigidly held against vertical sliding movement.

The invention further proposes to provide for latching the sash members against sliding movement when in any position of adjustment relatively to each other and to the window frame, and to provide for rendering the manipulating devices inaccessible from a position outside the window when the sashes are partly open.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is a longitudinal cross-section of the device in use.

Figure 2 is a detail end elevation.

Figure 3 is a plan view, and

Figure 4 is a fragmentary side elevation of one end portion of the device.

The window latch *a* of the present invention comprises a clamp portion *b* and a screw operated presser bar *c*. The clamp member *b* consists of a curved sleeve portion 5 which is open at one end for telescopically receiving a sleeve 6. The sleeves 5 and 6 carry at their outer ends jaws 7 and 8 which are provided for bearing on the opposite faces of the upper corner portion of the lower sash 9 of a window *d*, as shown in Figures 1 and 3. The connection between the sleeves 5 and 6 is such that these sleeves slide one upon the other so as to permit the jaws to be secured to varying widths of sash. An adjusting screw 10 is screwed into the jaw 8 which bears on the outer face of the lower sash 9 and a cylindrical extension 11 of the screw is journaled in the jaw 7 and terminates in a non-cylindrical end portion 12 which is adapted for insertion into the socket of a key or other suitable implement which may be employed for turning the screw 10, in ad-

justing the jaws to receive the lower sash 9 and for operating the jaws to clamp the said sash or to move out of engagement therewith.

The presser bar *c* is superimposed upon clamp *b* and the underside of the semi-circular body 12' has a longitudinally extending channel 13 which receives the upper segment of sleeve 5 upon which it is adapted to slide. A pair of oppositely disposed grooves 14 extend longitudinally of the opposite sides of the sleeve 5 and receive oppositely disposed ribs 15 arranged in the channel 13, and extending longitudinally thereof and disposed near the opposite longitudinal edges of the same. A lug 16 extends obliquely upward from one end of the body 12' and is arranged so as to bear upon one of the side rails of the upper sash 17. The wall of the channel 13 is screw-threaded, as indicated by 18, and a correspondingly screw-threaded groove is provided upon the upper side of the sleeve 5 disposed within the channel. The presence of the screw-threaded groove cooperates with the channel to provide a screw-threaded hole for an adjusting screw 19 which is held against endwise movement within the presser bar by a rib 20 disposed in a circular groove 21 in one end portion of the screw. The screw terminates at one end in a non-cylindrical boss 22 which is adapted to fit into the socket of a key or other suitable operating implement.

It will be noted that the non-cylindrical end portions 12 and 22 of the screws 10 and 19 are disposed underneath overhanging portions 23 and 24 which are respectively disposed on the inner jaw 7 and inner end of the presser bar *c*. The presence of the overhanging portions 23 and 24 conceals the end portions 12 and 22 of the screws from the outside of the window, and thereby prevents access being had to the said end portions of the screws from a position outside of the window while the device is in use and holding the sash members locked in open position.

In using the device, the clamp member *b* is adjusted to receive the upper corner portion of the lower sash 9 after which the screw 10 is turned which causes the jaws 7 and 8 to bind upon opposite portions of the lower sash 9. In this connection one of the jaws as, for instance, the jaw 8 may be provided with a spur 25 on its inner face to embed into the adjacent surface of the

sash rail and thereby defeat any attempt to slide the clamp from engagement with the lower sash member 9. By turning screw 19 the lug 16 is caused to bear upon the adjacent side rail of the upper sash 17 and forces the same outwardly so as to bind upon the surface of its guide and, at the same time, the lower sash 10 is forced inwardly and binds upon the guide for the same. In this way both sashes are frictionally held against vertical movement in any of their adjusted positions.

Although I have shown and described one embodiment of my invention, it is to be understood that the same is susceptible of various changes; and I reserve the right to employ such as may come within the scope of the appended claims.

I claim:

20 1. A latch for the upper and lower sash members of a window comprising a clamp having relatively movable jaw members adapted to be detachably connected to one of the upper corners of the lower sash and a 25 presser bar slidably connected to the clamp and adapted to bear outwardly upon a side rail of the upper sash, and means connecting the clamp to the presser bar for operating the latter to move into and out of contact 30 with the upper sash.

2. A latch for the upper and lower sashes of a window comprising a clamp including oppositely disposed and relatively movable jaw members adapted to be detachably connected to one of the upper corner portions of 35 the lower sash and a presser bar slidably connected to the clamp and adapted to bear outwardly upon a side rail of the upper sash, and cooperating structures including a screw connecting the clamp to the presser bar and 40 adapted for operating the presser bar to move into and out of contact with the upper sash.

3. A window sash latch comprising a clamp having oppositely disposed and relatively movable jaw members and telescoping sleeve portions connected to the jaw members, a screw extending through the jaw members for operating the same to move toward and away from each other, one of 50 said jaw members being provided with an overhanging portion extending beyond one end of the screw, a presser bar slidably connected to one of the sleeve portions and the clamp and having at one end a laterally extending lug and means connecting the presser bar to the clamp and for operating the same to slide upon the clamp.

ALEXANDER T. GIBSON.
